UNITED STATES PATENT OFFICE.

EDWARD J. DOLAN AND PASCHAL TATORE, OF NEW YORK, N. Y.

APPARATUS FOR RAISING AND LOWERING MATERIALS.

Application filed July 10, 1922. Serial No. 573,930.

To all whom it may concern:

Be it known that we, EDWARD J. DOLAN and PASCHAL TATORE, citizens of the United States, and residents of New York, State of New York, have invented certain new and useful Improvements in Apparatus for Raising and Lowering Materials, of which the following is a specification.

This invention relates to apparatus for 10 raising and lowering material of various kinds and more particularly the various pieces of scenery, technically referred to as "drops" or "flats", which are employed in the different acts and scenes during the presentation of a play or other performance of a theatrical nature.

The invention will hereinafter be described with reference to the raising and lowering of drop-scenes, but it must be clearly 20 understood that it is applicable to various fields of industry where such movements of units employed therein are required.

Heretofore, with the exception of one or two electrically operated devices, the various drop-scenes which go to make up a scene in a play or the like have been lowered from above the top of the stage, where they are kept when not in use, down within the "view" of the proscenium and vice versa, by manual labor.

The object of the present invention is to provide improved and simplified electricaly-operated means for this purpose, which will be efficient in operation, and comparatively inexpensive to install and operate.

The invention consists in the mechanism and in the combination and arrangement of its various parts to be hereinafter described and finally embodied in the claims.

Referring to the accompanying drawings, which illustrate one embodiment of the invention, and in which corresponding characters of reference indicate like parts in the several views:

Figure 1 is a front elevation of a device constructed according to the present invention.

Fig. 2 is a view, taken at a right angle to Fig. 1, showing partly in elevation and partly in section, the mechanism employed for raising and lowering individually different drop-scenes.

Fig. 3 is a plan view of the mechanism shown in Fig. 2.

Fig. 4 is a sectional view, on an enlarged

scale, of part of the mechanism shown in Fig. 2.

Fig. 5 is a horizontal sectional view of part of the mechanism shown in Fig. 4.

Fig. 6 is a vertical section, on an enlarged 60 scale, of an electric circuit make-and-break device shown in Fig. 2, and,

Fig. 7 is a diagrammatic representation of the wiring of the electric circuits necessary to operate the mechanism shown in the other figures of the drawings.

Referring more particularly to Figure 1 of the drawings, the numeral 1 indicates the proscenium opening, 2 a drop-scene lowered into place therein, and 3 the front 70 members of the main supporting framework, which latter is constructed and arranged to support the mechanism hereinafter to be described in the most convenient manner, and preferably comprises the said two front 75 members disposed at either side of the stage and two similarly positioned members at the back of the stage at either side thereof.

Each drop-scene is detachably connected, as by the usual means 4, to preferably four 80 ropes 5 as shown as is also usual, and these ropes pass respectively over pulleys 6 rotatable in bearings carried by a cross beam 7. Each rope is then led to and around an upper block 8 and a lower block 85 9 and its end is hooked on to the upper block 8 in the well-known manner.

The upper blocks 8 are of the usual well-known construction, those shown in the drawings being of the triple sheave type and are connected to and suspended from an inwardly-projecting bracket 10 carried by and extending between the front and rear members of the main frame at one side of the stage, but the lower blocks 9 are constructed as hereinafter described, and form a part of the drop-scene raising and lowering mechanism hereinafter to be explained. Such mechanism, in Figure 1, is indicated in a general manner by the numeral 11 and 90 from such figure it will be seen that the same is supported upon a platform 12 carried by the same front and rear members of the main frame at one end of the stage as carry the bracket 10.

Such mechanism will now be described in detail with reference more particularly to Figures 2 to 6 inclusive of the drawings. It must first of all be understood however, that the various scenes are arranged one be- 105 110

hind the other as in manually operated devices; that each drop-scene is connected as above stated by four ropes to a similar number of upper blocks 8 and lower blocks 9; and that, according to the present invention, mechanism is provided for mechanically raising or lowering each drop-scene individually by electric power. As the mechanism for each drop-scene is the same, 10 a description of one will answer for all such mechanisms.

As will be seen from Figures 1 and 2, the four ropes 5 which support the drop-scene 2 pass over sheaves housed within the lower block 9 which is rectangular in shape, and such block is centrally bored and the bore screw-threaded to receive, and work up and down upon, a screw 13. From Figure 2 it will be apparent that each individual rope 20 5 is passed over three sheaves arranged side by side in the lower block 9, so that with the construction shown there will be twelve sheaves in all in said block to support one drop-scene.

25 The upper end of screw 13 works in a bearing formed integral with a plate 14 adapted to be secured in any convenient manner to a cross beam 15 carried by the main frame or to a wall at one side of the stage. The lower end of the screw is of reduced diameter to form a plain shaft 16 centrally disposed within the casing 17 provided with openings 18 (see Figure 1) at either side for the purpose hereinafter described.

30 The upper end of the casing 17 is provided with an integral extension 19 bored to permit the shaft 16 to pass therethrough and freely revolve therein and forms, together with a sleeve 20 on the underside thereof, 40 a thrust bearing. Below the thrust bearing on the shaft 16 there is loosely mounted one part 21 of a clutch (which acts both as a clutch and as a gear as later described) provided with downwardly projecting pins 22 adapted to engage projecting studs 23 45 formed on the upper face of another part 24 of the clutch which is keyed or otherwise secured to the shaft 16 but which at the same time is capable of longitudinal movement thereon. On its under face the part 24 of the clutch is provided with a second series of studs 25—this time downwardly projecting—adapted to be engaged by upwardly projecting pins 26 formed on a third 50 part 27 of the clutch member which is free to revolve on the shaft 16 but prevented from longitudinal movement thereon by a collar 27* fixed thereto. A similar collar 21* prevents longitudinal movement of the clutch member 21 on said shaft.

55 The lower block 9 works in and is guided by guide rails 28 which are bolted to casing 17 and bracket 14.

Within the casing 17 at diametrically opposed points are arranged a pair of solenoids

30, 31, the cores 32 of which extend respectively loosely through and beyond clutch couplings 33 and 34 respectively arranged toward the opposite ends of the member 24 of the clutch. To the end of each core 32 is fixed at a right angle thereto a connecting piece 35 and to each latter is connected, at a similar angle, a rod 36. As the solenoids 30, 31 are reversed with respect to each other rods 36 will consequently operate in opposite directions but both are provided for the purpose of releasing at the desired times a 70 brake band 37 engaging the clutch member 24 at or about its center and normally preventing the longitudinal movement of the clutch member 24 on the shaft 16. The brake band 37 grips the said member 24 normally through the action of springs 38, one end of each of which bears against the inside of the casing 17 and the other end against lugs 39 formed integral with each end of the band 37 which is, as will be seen from Fig. 5, formed in two parts. Nuts are preferably provided for adjusting the tension of said springs. The rods 36—which are reduced 80 conically about the center of their length—are adapted to open out the two lugs 39 at opposite sides of the band 37 respectively in order to release the said band and consequently the clutch member 24 at the times 85 desired.

90 The operation of the mechanism so far described may be explained as follows:—

95 The solenoids 30 and 31 respectively form part of two different electric circuits, so that when it is desired to operate either solenoid it is only necessary to close the switch in the proper circuit. Suppose then, for example, that the solenoid 30 is energized in this manner; its core 32 will be drawn thereinto and the conical portion of its connected rod 36 will open out the lugs 39 at the right hand side of Fig. 4, thus opening the brake band 37 and releasing the clutch member 24. This member will not however be moved longitudinally on the shaft 16 immediately but will only be moved in a downward direction thereon on the connecting piece 35 coming into contact with the coupling 33 fixed to said member. Now, means are provided for rotating the clutch member 27 constantly on but independently of the shaft 16 as will hereinafter appear and therefore on the clutch member 24 engaging the member 27 through the medium of the studs 25 and pins 26, the member 24 will be revolved by the member 27 and hence the shaft 16 and its integral screw 13 will be turned. This will move the block 9 vertically on the screw and so alter the length of the ropes 5 connected thereto and to the blocks 8, which variation will in turn move the drop-scene in one direction. When it is desired to move the same scene in the opposite direction the solenoid 31 will be energized through the closing of 100 105 110 115 120 125 130

the appropriate circuit and the same action as above described will take place except that the clutch member 24 will be moved upward on the shaft 16 to engage the member 21 instead of downwardly to engage the member 27 as before. In this case the member 21 also constantly rotates on the shaft 16 (by means to be later described) but in a direction opposite to the member 27; hence the screw 13 will rotate in the opposite direction and the block 9 will also move in the reverse direction.

A spring 40 is provided for returning the clutch member 24 to its normal position from engagement with the clutch member 27 after the electric circuit has been broken on the completion of the desired movement of the scene. The clutch member 24 will return to its normal position from engagement with the member 21 by gravity—hence no spring is provided for this movement. To return the solenoid cores 32, their connecting pieces 35 and rods 36 to their normal positions, a spring 41 is provided on each of the latter, one end of each spring taking a bearing against a bracket 42 supporting the solenoid and the other end against the end of the conically reduced part of the rod 36.

It is necessary, as above pointed out, to provide mechanism for raising and lowering each drop-scene individually. In Figs. 2 and 3 mechanism for raising and lowering five different drop-scenes is shown by way of example only, and it must be understood that the apparatus is so constructed as will readily permit of handling the necessary number of individual scenes required in any particular theatrical production.

In order to be able to handle the total number of drop-scenes in an efficient manner, the following driving mechanism is employed:

An electric motor 50 (see Fig. 7) is provided and its shaft 51 (see Fig. 2) is provided with a bevel wheel 52, which meshes with clutch member 21 of one of the drop-scene shifting mechanisms hereinbefore described, preferably, as shown in Fig. 2, with the center mechanism of the group. The clutch member 21 of this particular mechanism is formed with a horizontally-disposed bevel wheel 54 and an integral spur wheel 55. The clutch members 21 of the remaining mechanisms are merely formed with a spur wheel 55 which gear with one another so that the drive of the motor shaft is communicated to all the clutch members 21. This will provide means whereby each screw 13 can be rotated in one direction on the clutch members 24 being brought into engagement with their individual members 21. In order to provide means for rotating the individual screws in the opposite direction, the spur wheel 55 of the rear mechanism

shown in Figs. 2 and 3 (see right-hand side of the drawing) is provided with an integral bevel wheel 56 which meshes with a vertically disposed bevel wheel 57 free to rotate on a stub shaft 58 carried by the rear casting 17. This bevel wheel meshes in turn with a bevel wheel 59 formed integral with the clutch member 27 of the rear mechanism, which clutch member also includes a spur wheel 60. The remaining clutch members 27 are each formed with a spur wheel 60, and hence motion is imparted to all the members 27 through the train of wheels so provided.

This arrangement permits of the motor 50 being started and kept running continuously as long as there are drop-scenes to be moved; it is only then necessary, to move any one drop-scene to close the proper electric circuits to energize the proper solenoids 30 and move the related clutch members 24 into engagement with either of their co-operating members 21 or 27 thus bringing about the revolution of the desired screws 13 and so raising or lowering the desired drop-scene or scenes.

The openings 18 in the casings 17 permit the spur wheels 55 and 60 to extend beyond the casing and mesh with the next adjacent wheels.

The electric circuits are shown diagrammatically in Fig. 7 from which it will readily be appreciated that the solenoid 30 or 31 of each mechanism can be energized at will, to raise or lower a drop-scene, by closing the switch 70 to complete a circuit through the terminal 71 or 72. In practice each switch 70 would be identified by a reference to the particular drop-scene which it controls. Further description of this particular figure is not deemed necessary as the connections will be readily understood by those skilled in the art.

Apart from the means for making and breaking the individual circuits just described, there is provided automatic means for breaking any circuit, in the case, for example, where any particular circuit has been made and then overlooked either through neglect or other causes.

To accomplish this, on either side of each screw 13 is arranged a rod 80 of any suitable non-conducting material, such as wood. The upper end of each rod slides in a bearing 81 and the lower end of each rod is guided by and free to move vertically in a small contact box 82 also made of non-conducting material, but provided with two copper contact pieces 82* to which are respectively connected two ends of the lead 83 in one case and of the lead 84 in the other case (see also Fig. 7). The lower extremity of each rod 80 is provided with a tip 85 of a conducting material, such as copper. Adapted to slide on each rod but with capa-

bility of being fixed thereto in any desired position by a set screw 86 is a stop 87 which extends into the path of the block 9. Each block 9 as above indicated is provided with 5 two such rods 80 and stops for the reason that as the block can operate in either direction it is necessary to provide one stop above and the other below the block, that is to say, one stop 87 must be provided in each of the 10 two circuits which control respectively the solenoids 30 and 31 of each mechanism.

The operation of the device under description shown at the left-hand side of the left-hand screw 13 in Fig. 2 may be described 15 as follows:—

The rod 80 will normally be held with its conducting tip 85 making contact with the two contacts 82* but on the block 9 coming into contact with the stop 87 the latter 20 will be depressed and with it the rod 80, and the conducting tip 85 will be forced down into the contact box 82 out of contact with the said contacts 82*, thus breaking the circuit and stopping the revolution of 25 the screw and consequently the movement of the drop-scene. A spring 88 returns the rod 80 to its normal position on the release of the stop 87. The operation of the device at the right-hand side of the said screw 30 13 is the same in principle as that above described, but in this case as the stop 87 is above the block 9 the rod will be raised on said block moving upwardly into contact with the stop. Furthermore, no spring 88 35 is necessary here as the rod will fall by gravity on the release of said stop.

It will be readily appreciated that the stops 87 may be fixed, by means of the set screws 86, in any position on their rods so 40 that the movement of the various drop-scenes can be arrested at any point in their travel that may be desirable.

What we claim and desire to secure by Letters Patent is:—

45 1. Apparatus for raising and lowering a unit of material comprising two electric circuits, a solenoid in each circuit, a shaft, a pair of spaced-apart clutch members free to revolve on said shaft but fixed against longitudinal movement thereon, means for rotating said clutch members in opposite directions, a third clutch member keyed to the shaft but capable of longitudinal movement thereon located between said two first-mentioned clutch members, a brake band normally holding said third clutch member against longitudinal movement on the shaft, means carried by the core of each solenoid for releasing the brake band and drawing the third clutch member into engagement with either of the two spaced-apart clutch members to rotate the shaft in one direction or the other, an endless screw integral with the said shaft, a block adapted to move longitudinally on said screw on its revolution, flexible connections from said block to the unit of material, means for making and breaking the electric circuits, and means for automatically breaking such circuits after a predetermined movement of the block, for the purpose stated.

50 2. Apparatus for raising and lowering a unit of material comprising two electric circuits, a solenoid in each circuit, a shaft, a pair of spaced-apart clutch members free to revolve on said shaft but fixed against longitudinal movement thereon, means for rotating said clutch members in opposite directions, a third clutch member keyed to the shaft but capable of longitudinal movement thereon located between said two first-mentioned clutch members, a brake band normally holding said third clutch member against longitudinal movement on the shaft, means carried by the core of each solenoid for releasing the brake band and drawing the third clutch member into engagement with either of the two spaced-apart clutch members to rotate the shaft in one direction or the other, an endless screw integral with the said shaft, a block adapted to move longitudinally on said screw on its revolution, flexible connections from said block to the unit of material, means for making and breaking the electric circuits, and means for automatically breaking such circuits after a predetermined movement of the block, for the purpose stated.

55 flexible connections from said block to the unit of material, and means for making and breaking the electric circuits, for the purpose stated.

2. Apparatus for raising and lowering a unit of material comprising two electric circuits, a solenoid in each of said circuits, a shaft, a clutch member fixed against rotation but capable of longitudinal movement on said shaft, means for connecting said clutch member to the two solenoids, two further clutch members respectively located at opposite ends of the first-mentioned clutch member and free to revolve on the shaft but fixed against longitudinal movement thereon, means for rotating said two clutch members on the shaft in opposite directions, an endless screw integral with said shaft, a block adapted to move longitudinally on the screw, flexible connections from said block to the unit to be operated, and means for closing either electric circuit to energize either one or the other solenoid to move the first-mentioned clutch member into engagement with one of the two further clutch members to rotate the screw in one direction or the other and raise or lower the unit of material accordingly.

3. Apparatus for raising and lowering a unit of material comprising two electric circuits, a solenoid in each circuit, a shaft, a pair of spaced-apart clutch members free to revolve on said shaft but fixed against longitudinal movement thereon, means for rotating said clutch members in opposite directions, a third clutch member keyed to the shaft but capable of longitudinal movement thereon located between said two first-mentioned clutch members, a brake band normally holding said third clutch member against longitudinal movement on the shaft, means carried by the core of each solenoid for releasing the brake band and drawing the third clutch member into engagement with either of the two spaced-apart clutch members to rotate the shaft in one direction or the other, an endless screw integral with the said shaft, a block adapted to move longitudinally on said screw on its revolution, flexible connections from said block to the unit of material, means for making and breaking the electric circuits, and means for automatically breaking such circuits after a predetermined movement of the block, for the purpose stated.

4. Apparatus for raising and lowering material, comprising a plurality of mechanisms to be driven including a shaft for each unit of material, a driving member having a shaft, a pair of spur wheels free to rotate on each mechanism shaft, connections whereby motion imparted to the driving member shaft will be imparted to the spur wheels, a clutch member located between the pair of spur wheels on each shaft,

- two electric circuits for each mechanism, a solenoid in each circuit, a brake band normally holding each clutch member against longitudinal movement on its shaft, 5 means carried by the core of each solenoid for releasing the brake band and drawing the clutch member into engagement with either of the two spur wheels of each mechanism to rotate the shaft in one direction or 10 the other, an endless screw integral with each mechanism shaft, a block adapted to move longitudinally on each screw on its revolution, flexible connections from each block to a unit of material, and means for 15 making and breaking the electric circuits of each mechanism.
5. In apparatus for raising and lowering material, a shaft, a pair of spaced-apart spur wheels free to rotate thereon, means for rotating said wheels in opposite directions, a clutch member located between said spur wheels and keyed to the shaft but free to move longitudinally thereon, a brake band normally engaging said clutch member to 20 prevent said longitudinal movement, two electric circuits, a solenoid in each circuit, means for connecting said clutch member to the two solenoids, and means for closing either electric circuit to energize either one 25 or the other solenoid to release the brake band and move the clutch member into engagement with either one or the other spur wheel to rotate the shaft in one direction or the other.
- 30 6. In apparatus for raising and lowering material, a shaft, a pair of spaced-apart spur wheels free to rotate thereon, means for rotating said wheels in opposite directions, a clutch member located between said spur wheels and keyed to the shaft but free to move longitudinally thereon, a brake band normally engaging said clutch member to prevent said longitudinal movement, two electric circuits, a solenoid in each circuit, 35 means for connecting said clutch member to the two solenoids, and means for closing either electric circuit to energize either one or the other solenoid to release the brake band and after a lapse of time to move the clutch member into engagement with either one or the other spur wheel to rotate the shaft in one direction or the other.
- 40 7. In apparatus for raising and lowering material, a shaft, a pair of spaced-apart spur wheels free to rotate thereon, means for rotating said wheels in opposite directions, a clutch member located between said spur wheels and keyed to the shaft but free to move longitudinally thereon, a brake band normally engaging said clutch member to prevent said longitudinal movement, two electric circuits, a solenoid in each circuit, 45 means for connecting said clutch member to the two solenoids, and means for closing either electric circuit to energize either one or the other solenoid to release the brake band and after a lapse of time to move the clutch member into engagement with either one or the other spur wheel to rotate the shaft in one direction or the other.
- 50 8. Apparatus for raising and lowering a unit of material comprising two electric circuits, a solenoid in each circuit, a shaft, a pair of spaced-apart clutch members free to revolve on said shaft but fixed against longitudinal movement thereon, means for rotating said clutch members in opposite directions, a third clutch member keyed to the shaft but capable of longitudinal movement thereon located between said two first-mentioned clutch members, a brake band normally holding said third clutch member against longitudinal movement on the shaft, means carried by the core of each solenoid for releasing the brake band and drawing the third clutch member into engagement with either of the two spaced-apart clutch members to rotate the shaft in one direction or the other, an endless screw integral with the said shaft, a block adapted to move longitudinally on said screw on its revolution, flexible connections from said block to the unit of material, means for making and breaking the electric circuits, means for automatically breaking such circuits after a predetermined movement of the block, and means for altering the position at which such automatic break is made.

Signed at New York in the county of and State of New York this first day of July, A. D. 1922.

EDWARD J. DOLAN.
PASCHAL TATORE.
